CONTROL CIRCUIT FOR ELECTRIC FURNACE
Louie O. Wicks, South Windham, Maine, assignor to
Portland Copper & Tank Works, Inc., South Portland,
Maine, a corporation of Maine
Filed July 20, 1962, Ser. No. 211,172
5 Claims. (Cl. 219—492)

This invention relates to electric furnaces and more particularly to improvements in circuits utilized for controlling the amount of current passing through the heater elements of such furnaces.

In the employment of electric furnaces in industry an important maintenance problem involves the replacement of heater elements. It has been discovered that the life of these elements is markedly decreased by the application of full line voltages to these elements when they are cold. These relatively high voltages applied to the cold elements cause surges of current through them which are many times greater than the normal operating currents. This is due to the fact that when cold, the heater elements have relatively low resistances compared with their resistance values after they have been heated. The result of these current surges through the elements is that the life of an element is greatly decreased.

This shortcoming is overcome by the improved control circuit of this invention which applies reduced voltages to the heater elements during warm up and thereafter applies full line voltage to them, thus greatly diminishing the initial drastic current surges which injure the elements.

Another object of the invention is to utilize the heater elements themselves as the current controlling devices with a minimum of external current control devices being required.

A further object of the invention is to provide control circuitry which is compatible with electric furnaces operating on direct current, single phase alternating current or three phase alternating current.

The foregoing objects are accomplished by providing a relay circuit for controlling the opening and closing of a plurality of contacts in the heater element circuit to change the electrical relationship of the heater elements with respect to one another.

Other objects and advantages will be apparent from the following description of the invention, pointed out particularly in the appended claims, when the foregoing are taken in connection with the accompanying drawings of illustrative embodiment of the invention in which:

FIGURE 1 is a diagram of the preferred form of the relay portion of the control circuit according to this invention;

FIGURE 2 is a schematic diagram of a three element heater operating on a three phase supply, the elements being interconnected under the control of the circuit of FIGURE 1;

FIGURE 3 is a schematic diagram of a two element heater operating on a single phase alternating current supply or on direct current, the elements being interconnected under the control of the circuit of FIGURE 1; and,

FIGURE 4 is a schematic diagram of a three element heater operating on a three phase supply, the elements being transformer coupled from a primary circuit which is interconnected under the control of the circuit of FIGURE 1.

Referring to FIGURE 1 the relay portion of the control circuit may be described. Across a source of control voltage 10 is connected a series arrangement comprising thermostat contact 12, a normally closed relay contact 14, and the winding of a relay 16. In parallel with relay 16 is the winding of a timing relay 18, having an ad-

2

justable timing cycle, and across the combination of contact 14 and relay 16 are contact 20 and the winding of a relay 22. Contact 20 operates on energization of timing relay 18. In parallel with contact 20 is another contact 24, which along with contact 14, is operatively related to relay 22.

In operation thermostat 12 closes when power is to be supplied to the furnace. This completes a circuit through normally closed relay contact 14 and relay 16. The energization of relay 16 occurs simultaneously with that of timing relay 18 in parallel therewith. On completion of a timing cycle commenced by the energization of relay 18, contact 20 is closed allowing relay 22 to be energized. This closes contact 24 and opens contact 14 thereby cutting off the voltage supply to relays 16 and 18. The de-energization of relay 18 opens contact 20 and current flows through the circuit comprising contacts 12 and 24 and relay 22. This condition exists until contact 12 is opened at the end of the heating period.

The application of power to the heater elements of an electric furnace under the control of the sequence just outlined will be described by referring to FIGURE 2. In this embodiment the ends of each of three heater elements 26, 28 and 30 are connected to a three phase power supply by leads L₁, L₂ and L₃ respectively. The other ends of the heaters are connected through contacts R_{1a} to a common junction point. Between input line L₁ and the contact side of element 30 is connected a first contact R_{2a}. Similarly, a second contact R_{2a} is provided between line L₂ and the contact side of heater 26, and a third contact R_{2a} is joined between line L₃ and the contact side of element 28. Contacts R_{2a} operate simultaneously with contacts 14 and 24 shown in FIGURE 1.

During the operation of the relay portion of the control circuit as described with reference to FIGURE 1, the energization of relay 16 causes contacts R_{1a} to close providing power to the three heater elements from the three phase supply. With these contacts closed and contacts R_{2a} open, the elements 26, 28 and 30 are joined in a star connection. As is well known, such a connection permits only a portion of the line voltage to appear across each heater element. This allows the heaters to gradually warm up without exposure to the severe current surges which would exist if full line voltage were initially applied to the elements.

It will be recalled that the energization of relay 22 of FIGURE 1 occurs essentially simultaneously with the de-energization of relay 16, the time of both actions being determined by the timing cycle established by relay 18.

With timing relay 18 adjusted to complete a timing cycle equal in time with the heater elements reaching a desired condition of gradual heating, contacts R_{2a} are closed on energization of relay 22 while contacts R_{1a} open due to the de-energization of relay 16. The connection between elements 26, 28 and 30 is thereby changed from a star configuration to a delta connection under which full line voltage is applied to the individual elements to effect increased heat generation by the elements.

Referring to FIGURE 3 a two heater element unit is shown for use with the circuit of FIGURE 1 and with a direct current (D.-C.) supply or a single phase alternating current (A.-C.) source. More specifically, the heater elements are supplied by input lines L₁₁ and L₁₂. Elements 32 and 34 are connected in series with contact 60 R_{1b} across the supply, contact R_{1b} being positioned between one end of element 32 and line L₁₁. Between line L₁₁ and the junction of elements 32 and 34 there is provided a first contact R_{2b}. An additional contact R_{2b} is connected between line L₁₂ and the heater side of contact R_{1b}. During initial operation of the circuit of FIGURE 1, the energization of relay 16 closes contact R_{1b} connecting elements 32 and 34 in series with the supply

causing the voltage to be divided across each element. When relay 16 is de-energized and relay 22 is simultaneously energized, contact R_1b opens and contact R_2b closes connecting both elements in parallel across the supply. Thus, the heater elements are gradually heated by the initial low voltage condition existing thereacross before being subjected to full line voltage.

The embodiment of FIGURE 4 is very similar in operation to the arrangement shown in FIGURE 2. A three phase power supply is coupled by input lines L_{21} , L_{22} and L_{23} and a three phase transformer 42 to heater elements 36, 38 and 40, connected in delta configuration across the secondary windings of the transformer. In the primary circuit there are provided contacts R_{1c} and R_{2c} as shown. During the operation of the relay control circuit of FIGURE 1, energization of relay 16 closes contacts R_{1c} to complete a star connection of the transformer primary windings. Thus, only a portion of full line voltage appears across each primary winding resulting in a coupling of partial voltage to the heater elements allowing them to gradually warm up. When relay 16 is de-energized, contacts R_{1c} open and contacts R_{2c} close due to the simultaneous energization of relay 22. The transformer primary windings are now connected in a delta configuration whereby they receive full line voltage which is coupled to the heater elements to increase the heat generation thereof. It can be appreciated that in this embodiment the electrical configuration of the heater elements is varied without a direct mechanical change thereto.

As can be seen from the foregoing, an improved electric furnace heater element control arrangement is provided whereby the heater is initially supplied less than full line voltage to gradually warm up to a condition at which full line voltage may be applied to complete the heating cycle. By such an arrangement, the difficulties caused by initial high current surges in the elements which reduce their life have been appreciably diminished. The improved control system differs from the prior art in utilizing the heater elements themselves with a minimum requirement of external temperature control devices.

The structural arrangements shown are examples of control arrangements in which the inventive features of this disclosure may be utilized, and it will be readily apparent to one skilled in the art that certain modifications may be made to the arrangements within the spirit of the invention as defined by the appended claims.

What is claimed is:

1. A circuit for controlling the heating cycle of an electric furnace comprising a plurality of interconnected heater elements, a source of control voltage, a series circuit including a thermostat contact, a normally closed contact and the winding of a first relay connected across said source, an adjustable timing relay winding in parallel with said first relay winding, a series circuit including a first normally open contact controlled by the timing relay and a second relay winding connected in parallel with the series connection of said normally closed contact and said first relay winding, a second normally open contact in parallel with said first normally open contact, the energization of said first relay winding by said source resulting in the interconnection of said elements in a first con-

figuration for period of time during the heating cycle determined by said timing relay, and the energization of said second relay controlling said normally closed contact and said second normally open contact resulting in the interconnection of said elements in a second configuration during the remaining portion of said heating cycle to effect the application of a first voltage value to said heater element when connected in the first configuration and a second voltage value of greater magnitude than said first value when said elements are connected in the second configuration.

2. A control circuit for an electric furnace comprising a source of control voltage, a first relay means energized by said source, a first contact means conditioned in response to the energization of said first relay means, a plurality of interconnected heater elements, said heater elements being interconnected in a first configuration on conditioning of said first contact means to apply a first voltage value to said elements; a timing relay energized simultaneously with said first relay means, a second relay means operatively related to said timing relay for connection to said source at a time after the energization of said timing relay dependent on the cycle of the timing relay, means for de-energizing said first relay means on energization of said second relay means; a second contact means conditioned in response to the energization of said second relay means, said heater elements being interconnected in a second configuration on conditioning of said second contact means to apply a second voltage of greater magnitude than said first voltage to each of said heater elements.

3. A control circuit as set forth in claim 2 wherein said heater elements comprise three members, said heater elements being connected in a star configuration when the first contact means are conditioned and in a delta configuration when the second contact means are conditioned.

4. A control circuit as set forth in claim 2 wherein said heater elements comprise two members, said heater elements being connected in series when the first contact means are conditioned and in parallel when the second contact means are conditioned.

5. A control circuit as set forth in claim 2 further comprising transformer means, said transformer means having primary and secondary winding circuits, said primary winding circuit connected with said first and second contact means and said secondary winding circuit connected to said heater elements, the conditioning of said contact means determining the mechanical configuration of the primary circuit and the electrical configuration of the heater elements.
